UNITED STATES PATENT OFFICE.

ROBERT F. GILLIN, OF BROOKLYN, NEW YORK.

DESIGN FOR LETTERS FOR SIGNS.

SPECIFICATION forming part of Design No. 17,624, dated August 9, 1887.

Application filed June 3, 1887. Serial No. 240,188. Term of patent 7 years.

To all whom it may concern:

Be it known that I, ROBERT F. GILLIN, of Brooklyn, in the county of Kings and State of New York, have invented and produced a new 5 and original Design for Letters for Advertising-Signs, of which the following is a specification, reference being had to the accompanying drawings, forming a part thereof.

Figure 1 is a face view of one of the letters. 10 Fig. 2 is a face view of a sign made up of such letters.

The members composing the letters, according to this design, are of equal width. The ends are rounded and are provided with T-shaped ornaments representing hoop-skirt clasps. 15 Each letter is provided with a single small perforation near the top.

A is the main body of the letter, made up of members of equal width.

20 A² is a slender connecting-piece having the perforation or hole a.

B B represent clasps or fasteners, which are T-shaped and ornament the rounded ends.

In Fig. 2 I have shown several letters embodying this design. 25

The members composing the letters are im- 30 perforate, excepting the single small hole near the top of each letter. In the example shown in Fig. 1 the perforation is in the connecting-piece A².

I claim as my invention—

The design for letters for advertising-signs herein described and shown, the same consisting of letters having members of equal width and rounded ends provided with T-shaped ornaments representing hoop-skirt clasps, said letters having a perforation, a, at the top thereof, all substantially as herein set forth. 35

ROBERT F. GILLIN.
